UNITED STATES PATENT OFFICE.

ALBERT H. SOUTH AND JOHN C. BOSTWICK, OF ORSON, IOWA.

SAW-TIGHTENER.

SPECIFICATION forming part of Letters Patent No. 729,436, dated May 26, 1903.

Application filed December 31, 1902. Serial No. 137,310. (No model.)

To all whom it may concern:

Be it known that we, ALBERT H. SOUTH and JOHN C. BOSTWICK, citizens of the United States, and residents of Orson, in the county of Harrison and State of Iowa, have invented new and useful Improvements in Saw-Tighteners, of which the following is a full, clear, and exact description.

Our invention relates to certain novel and useful improvements in saw-tighteners, and has particular application to a device of the type mentioned for tightening the saw-blades in the frame of what is commonly known as a "bucksaw."

One of the principal objects contemplated in carrying out the present invention is to produce a tightener which may be readily and easily manipulated, whereby the saw-blade when it is loose or slack in the frame may be brought to the desired tension or tightness.

We also have in view the construction of a tightener which may be operated without the use of the ordinary set-screws or the like, whereby much time is saved, the only action necessary being the operation of a swinging lever which is connected with the friction-grip tightening means.

A further object of our invention is to construct a mechanism which shall be exceedingly simple and durable, capable of being readily attached to the frame of the saw and removed therefrom, and one which may be manufactured and sold at but little expense.

With the above-recited and other objects of a similar nature in view our invention consists in the peculiar construction, combination, and arrangement of parts, as will be hereinafter described in this specification, delineated in the accompanying drawings, and set forth in the appended claims.

Reference is to be had to the accompanying drawings, forming a part of this specification, in which similar characters of reference indicate corresponding parts in all the figures.

Figure 1 is a perspective view of a bucksaw having our improvement applied thereto. Fig. 2 is an enlarged detail view of our improved tightener, partly in section and

showing the position assumed by the parts 50 when they are in frictional locking engagement; and Fig. 3 is a view similar to Fig. 2, but showing the parts out of locking engagement, whereby the main rods of the tightener may be moved relatively to each other. 55

Referring now to the accompanying drawings, the frame of the saw, which is clearly illustrated in Fig. 1, is of an ordinary and well-known form, comprising the horizontally-extending bar 1 and the two approximately vertically arranged frame portions 2 and 3, the portion 3 being relatively longer than the portion 2 and is formed with a handle or grip 4. The saw-blade is also of any well-known or preferred form, as shown at 5, 65 and is riveted between the vertically-extending portions 2 and 3 of the frame. The upper ends of the vertical portions 2 and 3 are preferably grooved to receive the looped portions 6 and 7 of the rods 8 and 9, forming a 70 part of our improved tightener. As will be observed on reference to the drawings, these rods are arranged parallel to each other in slightly-different horizontal planes, the rod 9 being provided with a clip or bracket 10, 75 rigidly secured thereto. In the present instance the rods are formed of metal, and to the end of the rod 8 is secured the bifurcated portion 11 of the lever 12, said lever extending downwardly toward the main bar 1 80 of the saw-frame. As will be observed, especially on reference to Figs. 2 and 3, this lever 12 is pivoted at 11^a to the rod 8 in such manner that it may readily oscillate or swing, the rod 9 passing between the arms forming 85 the bifurcation of the lever and extending parallel with the rod 8 a short distance below the same. A second small horizontally-disposed bifurcated lever 13 is pivoted at one end 14 to the bifurcated portion of the main 90 lever and is adapted to pivotally receive, as at 15, the sliding block 16, which is provided with an aperture 17, through which the rod 9 extends. A spirally-coiled tension-spring 18 is wound around the rod 9 intermediate 95 the bifurcated portion of the main lever and the sliding block 16, said block being preferably provided with a handle or grip 19. A

second sliding block 20 is pivotally secured at 21 to the end of the rod 9, said block being similar in every respect to the block 16, having an aperture or bore 22 for the passage of the rod 8 and a handle-grip 23. A coiled spring 24, a counterpart of the spring 18, is wound about the rod 8 and bears at one end against the sliding block 20 and at the other end against the bracket 10.

From the above description, taken in connection with the drawings, the operation of our device will be readily apparent. The frame of the saw, which, as heretofore described, is of ordinary construction, has its central horizontal bar so socketed in the side bars of the frame that a saw-blade held at the lower ends of said side bars may be tightened or loosened, as desired, by tensioning the upper ends of the side bars—that is to say, when said ends are forced or drawn toward each other the saw-blade will be tightened and when the ends are allowed to move away from each other the lower portion of the side bars will be correspondingly thrown inwardly and the blade loosened. In Fig. 2 we have illustrated the position of the parts assembled by the tightener when they are in locking engagement. Now if it is desired to tighten the blade the rods must be moved or slid inwardly relative to each other until the distance between the looped portions is lessened, and this is accomplished by swinging the lever 12 back and forth. When the lever is swung on its pivot 11^a, the frictional locking engagement between the walls of the apertures 17 and 22 of the blocks 16 and 20, with the parallel rods, will be released and the rods will be fed inwardly toward each other and the vertical sides of the frame being drawn toward each other the blade will be tightened. When it is desired to loosen the blade, the sliding blocks may be fed inwardly toward each other by gripping the handle portion, and the rods may be moved outwardly and the distance between these ends may be readily lengthened. The springs, it will be observed, tend to retain the parts of the device in frictional locking engagement when it is desired to have the same remain stationary, as when the saw is in use.

There are many other advantages incident to our improvement which will readily be appreciated, so that it is unnecessary to describe the same in detail here.

While we have herein illustrated and described one particular embodiment of our invention we wish it to be understood that we do not consider ourselves as limited to the precise construction, as there may be modifications and variations in certain respects without departing from the essential features of the invention or sacrificing any of the advantages thereof.

Having thus described our invention, we

claim as new and desire to secure by Letters Patent—

1. A saw-tightener comprising two rods, means slidably mounted on each of said rods and normally resting in frictional contact therewith, and a device for sliding the means of one rod along the same and simultaneously drawing the other rod inward, the construction being such that the rods will be moved toward each other, substantially as set forth. 70

2. A saw-tightener comprising two rods movable relatively to each other, block for each of said rods slidably mounted on and frictionally engaging therewith, tension means for normally pressing each block in frictional contact with its rod, and a device connected with one of said rods and with the sliding block of the other rod, the construction being such that when said device is actuated the rods will be moved toward each other, substantially as set forth. 80

3. A saw-tightener comprising two rods movable relatively to each other and formed with loops at their outer ends, said loops being designed to fit over the bars of the saw-frame, a clip secured to one of said rods and designed to act as a guide for the other rod during its movement, a lever secured to the opposite rod from that carrying the clip, a sliding block mounted on and frictionally engaging with each of said rods, and a connection between the lever and one of said blocks, and the lever and one of the rods, the construction being such that when the lever is actuated the rods will be moved inward toward each other, substantially as set forth. 90

4. The combination with a saw-frame and a blade mounted therein, of a tightener therefor, said tightener comprising two rods adapted to engage the frame of the saw, a lever pivoted to the end of one of said rods, a block 105 slidably mounted on the other rod, a pivotal connection between the lever and said block, and a second block slidably mounted on the rod to which the lever is pivoted, the construction being such that the blocks are adapted to be normally held in frictional contact with said rods to lock the same against movement, but will permit the rods to be moved toward each other when the lever is actuated. 110

5. The combination with a saw-frame, a blade mounted therein and a tightener therefor, the latter comprising rods secured to the saw-frame, and arranged in parallelism, a main lever pivoted to the end of one of said rods, a sliding block pivoted to the end of the opposite rod and slidable along the first-mentioned rod, a second sliding block movable on the second rod, a link connection between the last-mentioned block and the lever, a clip on one of said rods, a spring interposed between the adjacent sliding block and the clip, and a second spring interposed

between the main lever and its adjoining sliding block, the construction being such that when the main lever is actuated the rods will be moved relatively to each other for 5 tightening the saw-blade in the frame, substantially as set forth.

In testimony whereof we have signed our

names to this specification in the presence of two subscribing witnesses.
